SUCTION CLEANER

Wilford G. Kilpatrick, Canton, Ohio, assignor to
The Hoover Company, North Canton, Ohio, a
corporation of Ohio

Application April 23, 1938, Serial No. 203,725

26 Claims. (Cl. 15—8)

The present invention relates to suction cleaners in general and particularly to new and novel surface agitating means in suction cleaners. More specifically the invention comprises a rotary agitator in a suction cleaner which is provided with surface-contacting agitating elements subjected to wear in use, and which are mounted for automatic adjustment to compensate for such wear.

It is an object of the present invention to provide a new and improved suction cleaner. It is another object of the invention to provide a new and improved suction cleaner rotary agitator. Still another object of the invention is to provide a rotary agitator with agitating means which are automatically adjustable to compensate for wear. A still further object of the invention is to provide a rotary agitator in a suction cleaner which agitator includes both rigid beating elements and flexible brush elements subjected to wear, the brush elements being so mounted that they are automatically adjusted to compensate for wear. A still further object of the invention is to provide a rotary agitator in a suction cleaner in which the agitating elements subjected to wear are automatically repositioned upon each use. Still another object of the invention is to provide a rotary agitator in which the brush bristles are readjusted to an optimum position at each use. These and other more specific objects will appear upon reading the following specification and claims and upon considering in connection therewith the attached drawings to which they relate.

Referring now to the drawings in which the same reference characters refer to the same parts throughout, and in which preferred embodiments of the present invention are disclosed:

Figure 1 is a front view of a suction cleaner embodying an agitator constructed in accordance with the present invention the cleaner nozzle being shown in section to disclose the agitator positioned therein;

Figure 2 is an enlarged partial longitudinal section through the agitator;

Figure 3 is a longitudinal view of the interconnected pivoted link plates which are attached to the radially movable brushes;

Figure 4 is a section upon the line 4—4 of Figure 1 and discloses the brushes positioned as with the agitator running;

Figure 5 is a view looking in the direction of the arrows upon the line 5—5 of Figure 1;

Figure 6 is a section upon the line 6—6 of 55

Figure 2 and shows the relationship of parts with the agitator running;

Figure 7 is a view similar to Figure 6 and shows the relationship of parts with the agitator standing;

Figure 8 is a section upon the line 8—8 of Figure 6;

Figure 9 is a section upon the line 9—9 of Figure 6;

10 Figure 10 is a view in perspective of the centrifugal weight;

Figure 11 is a section similar to Figure 6 through a second preferred embodiment of the invention with the parts in the running relationship;

15 Figure 12 is a view similar to Figure 11 but with the parts in the standing relationship;

Figure 13 is a section similar to Figures 6 and 11 through a third embodiment of the invention 20 with the agitator parts in the running relationship;

Figure 14 is a view similar to Figure 13 with the agitator parts in the standing relationship.

In the modern suction cleaner, the surface 25 agitating means cooperate with the moving air stream to effect dirt removal from the surface covering undergoing cleaning. The surface-agitating means in the cleaner normally comprise a rotating agitator body provided with rigid beating elements and flexible brushing elements. In operation the rigid beating elements, being made of hard metal are not subjected to wear. They extend, throughout the length of life of the agitator to substantially the same radial distance

30 from the center of rotation. The flexible brushing elements, however, usually comprise bristles which gradually wear away through repeated contacts with the surface covering undergoing cleaning, resulting in a decrease in their length. 35

40 If the flexible brushing elements are fixedly seated in the agitator within a relatively short period of time the bristles of the brushes wear down until the brush elements do not extend radially to the same distance as the rigid beater elements and thereafter the brush elements are substantially ineffective to perform their intended function.

In the suction cleaner rotary agitator constructed in accordance with the present invention 45 automatic means are provided which adjust the brushing elements to compensate for their decrease in bristle length.

This function is accomplished by new and novel means in a manner which will be hereinafter described.

Referring again to the drawings and to Figures 1 to 10, inclusive, in particular, the first preferred embodiment of the invention is disclosed. A modern suction cleaner is illustrated having a casing which includes a nozzle 1 having surface-contacting lips 2 and 3, a fan chamber 4 and a motor casing 5. An unshown motor within the casing 5 is formed with a downwardly extending shaft 6 which extends through the fan chamber 4 where it carries the suction-creating fan 7 which functions in the operation of the machine to create a reduced pressure which is effective within the nozzle 1 to draw cleaning air between the surface-contacting lips 2 and 3. The cleaner is movably supported upon the surface covering undergoing cleaning by wheels 8, 8 etc., while a handle 9, the lower forked bail arms 10, 10 of which are pivoted to the cleaner casing, provides means by which the machine can be propelled over a surface covering undergoing cleaning.

Removably positioned within the nozzle 1, in such position that it is adapted to contact a raised surface covering between the nozzle lips 2 and 3, is a rotary agitator 14 upon the cylindrical body 15 of which extend rigid helical beater bars 16, 16. Brush seats 17, 17 extend longitudinally in the body 15 between the beater elements and positioned therein are brushes 18, 18 formed with rigid backs 19, 19. Agitator body 15 is formed near its center with a circumferential groove which functions as a pulley, indicated by the reference character 21, and which is adapted to seat a power-transmitting belt 22 extending rearwardly into driving relationship with the lower end of the motor shaft 6 in a common and well known manner forming no part of the present invention.

The agitator is rotatably mounted within the nozzle by its supporting shaft 24, the extended ends of which are removably seated, in a common manner, within retaining means in the end walls of nozzle 1. The shaft 24 is itself non-rotatable and the body 15 is rotatably carried thereon by a suitable bearing 25 at each of its ends which is positioned between the shaft and the cup-shaped end wall 26. A thread guard 27 seats in screw threaded relationship upon the outer end of shaft 24 and contacts the inner race of bearing 25 to retain it against a shoulder formed by an enlarged portion 28 of the shaft. In normal operation the agitator rotates about the shaft 24 under the rotative force received from the power-transmitting belt 22 which is itself driven by the shaft 6 of the driving motor. Contact with the surface covering undergoing cleaning is effected as the latter is lifted into contact with the agitator and with the surface-contacting lips 2 and 3 by the suction within the nozzle 1 created by the suction-creating fan 7.

According to the present invention the brushes 18, 18 are slideable radially within their seats 17, 17, and means are provided which adjust each brush to the desirable radial position. The adjusting means positioned within the agitator, comprise, according to this embodiment of the invention, a centrifugal weight 30 which is pivoted to an inner body-carried wall 31, located adjacent the outer end of each brush seat 17, about a pivot pin 32. Weight 30 is adapted to contact the inner wall of cylindrical body 15 in its outer radial position and is at all times urged inwardly by the spring 33 the end of which slidably seats within a slot 34 formed in the side of weight 30. The inner side of the weight is toothed, as indicated at 35, for a purpose which will hereinafter

be apparent. In addition to being shaped to conform to the internal contour of cylinder 15 the weight 30 is also formed in the shape of an "L" between its ends and at the junction of the arms of the "L" is pivoted a lever arm 38 upon a pin 39. The end of the lever 38 which extends from the weight 30 is provided with teeth 40 while the portion which extends along and adjacent the weight 30 is formed upon one side as a cam surface 41. A coil spring 42 carried by the pin 39 10 at all times urges the lever 38 clockwise as viewed in Figures 6 and 7 to hold the cam surface 41 against a stop pin 42 throughout the angular movement of the weight 30 under centrifugal force.

With the agitator rotating the centrifugal weight 30 is thrown outwardly against the inner side of the enclosing agitator shell 15, as shown in Figure 6, but the strength of spring 33 is such that with the agitator standing the weight is forced radially inward to an inner position, as shown in Figure 7.

Seated for limited angular rotation upon the shaft-enclosing hub 45 of inner plate 31 is a rotatable plate 48 formed on its periphery at spaced points with toothed sectors 49 and 50 adapted to mesh with the teeth 35 and 40, respectively, which are formed on the centrifugal weight 30 and the lever arm 38. Rotatable plate 48 is connected by links 52 and 53 to the ends of rods 55, 55 which are, as is clearly seen in Figures 4, 6 and 7, positioned at the sides of the supporting shaft 24 and extend parallel thereto. Each rod is supported at each end within a slot 56 formed in the interior plate 31. The angularity of the links 52 and 53 is such that rotation of plate 48 in one direction serves to move the rods 55, 55 radially inward in their supporting slots 56, 56 while rotation of the plate in the opposite direction tends to move the rods outwardly.

A link plate 57 connects each rod 55 to a rigid brush back 19, the back being slideable within its own seat 17. As is clearly seen in Figure 3, the link plates pivotally enclose the rods 55, 55 and are connected at their opposite sides by an elongated bolt 58 carried by inwardly extending lugs 20, 20 formed on each brush back 19. It is clear from the relationship of parts that as the brush elements move radially outward the rods 55, 55 will be drawn radially inward and toward each other, and that a movement of the rods 55, 55 radially outward will result in an inward radial movement of the brush elements 18. As both brushes 18, 18 are joined to the longitudinally extending rods 55, 55 it is clear that the movement of the brushes will be conjoint. The opposite ends of the agitator are identical. Within the nozzle at spaced points are stop rings 60, 60 which encircle in spaced relationship the agitator with

60 in the nozzle adjacent the brush elements 18, 18. Each stop ring 60 comprises a smooth metal element which opens downwardly and which is fixed within the nozzle through having its lower overturned ends secured to the nozzle walls by screws 61, 61. These stop rings, being spaced radially beyond the rigid beater elements 16, 16, cannot be contacted thereby and are of such limited extent longitudinally of the agitator that they do not interfere with the free flow of air through the nozzle or with the foreign material which is carried therethrough.

The operation of the agitator constructed in accordance with the present invention is as follows:

The agitator in the standing position, that is

not rotating, is illustrated in Figure 7. The force exerted by the spring 33 has forced the weight 30 radially inward until its teeth 35 have meshed with the teeth 49 upon the rotatable plate 48. When so engaged the plate 48 cannot rotate, the rods 55, 55 are held fixed by the links 52 and 53, and accordingly the radial position of each brush 18 is determined as its rigid back 19 is connected by the link plates 57, 57 to the rods 55, 55. When the cleaner is placed in operation and the agitator begins to rotate, upon reaching a certain speed the centrifugal force exerted by the weight 30 will exceed slightly the opposing force exerted by the spring 33 and the weight will move radially outward to a sufficient extent to disengage the teeth 35 and 49 of the weight and of the plate 48, respectively. There is then nothing to oppose the outward radial movement of the brush elements 18, 18 under centrifugal force and those elements fly outwardly and into contact with the stop shoes or rings 60, 60. As the brushes are radially opposed one element thereof is at all times in contact with a stop shoe or ring. As the speed of the agitator increases the centrifugal weight is thrown radially outward and approaches the inner wall of the agitator body 15. Before actual contact of the weight with the wall is made the weight 30 has pivoted to a sufficient extent that the lever arm 38, which it carries and which moves therewith, has been moved sufficiently to engage its teeth 40 with the teeth 50 formed upon the rotatable plate 48. The lever 38 is not rigid with the weight 30 but changes its angular position relative thereto as the cam surface 41 formed thereon slides upon the pin 43. Contact of the lever arm teeth 40 with the teeth 50 of plate 48 does not prevent further outward radial movement of the weight 30 which instead continues to move until it contacts the inner surface of the enclosing cylindrical agitator wall 15. This additional movement of the centrifugal weight, that is, the movement which takes place following the contact of the teeth 40 with the teeth 50, causes the arm 38 to be drawn clockwise about the pivot 32, as viewed in Figures 6 and 7, thereby causing the plate 48 to rotate in a counter-clockwise manner, as illustrated in those two figures, resulting in the outward radial movement of the rods 55, 55 which are connected thereto through the links 52 and 53. As explained above, such outward radial movement of rods 55, 55 results in the inward displacement of the brush elements 18, 18 and this is just what is intended.

The lever arm 38 always engages the plate 48 at a certain angular position of the weight 30 and in moving radially outward under centrifugal force from that position to its outermost position at which it contacts the inner surface of the body 15 the lever arm moves the plate angularly through a definite arc. The displacement inwardly of the brush elements effected by that rotation of the rocker plate 48 is just sufficient to move them from contact with the enclosing shoes 60, 60 to reduce their radial extension to that of the rigid beater elements 16, 16.

During the continued rotation of the agitator the situation and condition therein does not change, but upon the motor being turned off and the agitator gradually decreasing its speed the spring force exerted by spring 33 will at some point overcome the centrifugal force exerted by the weight 30 and that element will be forced inwardly thereby releasing the lever arm 38 from engagement with the rocker plate 48. Thereaf-

ter, and before the agitator completely stops, the brushes will again fly outwardly under centrifugal force and upon the weight 30 being forced by the spring 33 into engagement with the rocker plate 48 the brushes will be locked at whatever radial adjustment they then have. Restarting the cleaner results in a repetition of the operation which positions the brushes in their operating relationship.

Referring now to Figures 11 and 12 in particular a second preferred embodiment of the invention is disclosed which differs from that previously described, only in the specific centrifugal weight and lever arm mechanism which adjusts the brush. In the first described embodiment the centrifugal weight had pivoted upon it the adjusting lever arm, whereas in the present embodiment the centrifugal weight and the adjusting lever arm are rigidly connected. According to this embodiment the rocker plate 70 is provided with toothed sectors 71 and 72 and is rotatable, as in the first embodiment, upon the hub 45 of the supporting plate 31 within the agitator body 15. Links 52 and 53 again connect the rocker plate to the longitudinally extending arms 55, 55 and, as in the first embodiment, rotation of the rocker plate 70 results in radial adjustment of the brushes 18, 18. The centrifugal weight in the present embodiment is indicated by the reference character 75 and is formed at its outer end with teeth 76 adapted to mesh with the teeth 71 upon the rocker plate 70. Weight 75 is pivoted upon the agitator wall 31 by a pivot pin 77 which is encircled by a coil spring 78 exerting at all times a force to pivot the weight 75 inwardly and which is opposed by the centrifugal force of the weight in the rotation of the agitator. Upon the opposite side of the pivot pin 77 from the teeth 76 the centrifugal weight 75 is formed as a lever 80 having a single tooth 81 at its outer end which is adapted to engage the teeth 72 also formed upon the rocker plate 70.

As in the first embodiment the weight 75 is thrown outwardly by centrifugal force in the rotation of the agitator causing its teeth 76 to disengage the rocker plate teeth 71, the weight having been held in that position by the spring 78. Thereupon the brushes 18 which are connected to the rocker plate 70 through the links 52 and 53 and the rods 55, 55, as in the first embodiment, fly outwardly into contact with the stop plate 60. Contact with the stop plate marks the outer radial limit of brush movement. Thereafter and upon the continued movement of the centrifugal weight 75 the tooth 81 of its lever arm 80, engages the teeth 72 of the plate 70. The length of the lever arm 80 is such that the first contact of the tooth 81 with the teeth 72 is not a binding contact but instead one which permits of the further movement of the weight 75 outwardly under centrifugal force. This further movement causes the lever arm 80 to pivot and to rotate the rocker plate 70 resulting in the movement of the links 52 and 53 and the inward movement of the brushes as in the first embodiment.

As in the first embodiment the centrifugal weight moves through a definite arc after its plate-rotating lever has engaged the plate and accordingly the plate is always rotated a fixed amount to draw the brushes inwardly a fixed distance from the stops 60, regardless of the position of the plate when engaged by the lever.

This plate position would, of course, vary as the brush became worn and its bristles shorter.

Upon the agitator coming to a stop when cleaner operation is discontinued the operation is substantially the reverse. As the agitator speed decreases to a certain point the force exerted by the spring 78 overcomes the centrifugal force exerted by the weight 75 and pivots it inwardly thereby disengaging the lever or pawl 80 from the teeth 72. The brushes 18 then tend to fly out and are locked in this outer position as clearly illustrated in Figure 12, by the cooperation of the teeth 76 with the teeth 71.

Referring now to Figures 13 and 14 the third preferred embodiment of the invention is disclosed. In this embodiment the brushes 18 are, as in the first two embodiments, suitably connected by link plates to the radially slideable rods 55, 55 positioned in the slots 56, 56 in the agitator plates 31. However, in the present embodiment the ends of the rods 55, 55 are squared and carry pinions 88, 88 which mesh with the teeth 89, 89 of a rack 90 carried by the wall 31. The centrifugal weight 92 in the present embodiment is again pivoted to the agitator wall 31 and by a pin 93. Weight 92 is formed with teeth 94 and beyond its pivot pin 93 is formed, as in the second embodiment, with a lever arm which is denoted by the reference character 95 which is itself formed with teeth 96. A coil spring 97 again encloses the pivot pin 93 of the weight and at all times urges the weight inwardly.

The relationship of the brush adjusting parts is as illustrated in Figure 14 with the brush standing. The centrifugal weight 92 has been forced radially inward under the action of the spring 97 until the teeth 94 at its inner end have meshed with the pinion 88, thereby securing it in place upon the rack 90 and preventing radial movement of the brush-connecting rods 55, 55. As the rods are connected by link plates 57, 57, as illustrated in Figure 3, a construction common to all three embodiments of the invention, the locking of one pinion 88 prevents the movement of both rods 55, 55 and so of the brush elements 18. Upon the rotation of the agitator and upon reaching a predetermined speed, centrifugal force moves the weight 92 outwardly against the force exerted by the spring 97 and the teeth 94 disengage the pinion 88. Thereupon the brushes 18 can move radially outward until they contact the stop shoes 60. The continued pivotal movement of the weight 92 under centrifugal force causes the teeth 96 of the latch lever 95 to contact the second pinion 88 thereby locking the construction in fixed position and preventing further movement of the parts during the operation of the device. As distinguished from the first two embodiments of the invention the lever 95 serves merely to latch or lock the brush 18 in place and does not serve to withdraw it radially inward from its contact with the stop shoes 60.

In all the embodiments of the invention the opposite ends of the agitator are identical. In each embodiment only one end of the agitator is shown but it is to be understood that the opposite end is similar thereto. The radially slideable rods 55, 55 slide in slots 56, 56 at each end of the agitator and, being connected to both brushes 18, 18 insure that they are synchronously adjusted.

It is to be understood that the invention is only herein illustrated in three preferred embodiments and that equivalent constructions en-

compassing the automatic readjustment to optimum positions of the agitating elements subjected to wear are within the scope of the invention, as set forth by the appended claims.

5 I claim:

1. In a rotary agitator for a suction cleaner, an agitating element subject to decrease in size with wear, means mounting said element for radial adjustment relative to the axis of rotation, and means controlled by the rotation of said element to reposition and fix said element in a predetermined optimum position under predetermined conditions of operation.

15 2. In a rotary agitator for a suction cleaner, a body, a brush adjustable relative to said body to compensate for wear, means to fix the position of said brush relative to said body and to release said brush under predetermined conditions, and means to adjust said brush to a predetermined optimum position under predetermined conditions of operation.

20 3. In combination in a rotary agitator for suction cleaners, a brush movable radially with respect to the axis of rotation, means to secure said brush in a fixed radial position when said agitator is inoperative and to release said brush at a predetermined speed of rotation, and means to secure said brush at a fixed radial position at a predetermined higher speed of rotation.

30 4. In a suction cleaner, a rotatable agitator including an agitating element subject to wear, stationary stop means adjacent said agitator adapted to limit the radial extension of said brush in the rotation of the agitator, and automatic means to move said brush and to lock said brush at a predetermined fixed optimum extension which is less than the extension at which said element contacts said stop.

40 5. In a suction cleaner, a rotatable agitator, an agitating element radially movable relative to the axis of rotation by centrifugal force and having an optimum position, stationary means to limit the outward displacement of said element to a radial extension slightly greater than its optimum position, and agitator-operated means to retract and hold said element at its optimum radial position at which it does not contact said stationary means during agitator rotation.

60 6. In a suction cleaner, a rotatable agitator, an agitating element movable radially with respect to the axis of rotation of said agitator by centrifugal force, means to prevent movement of said element below a predetermined speed of rotation only, stationary means to limit the outward displacement of said element, and means operative at a higher speed to retain said element at a fixed radial extension.

7. In a suction cleaner, a rotatable agitator, an agitating element movable radially with respect to the axis of rotation of said agitator by centrifugal force, means to prevent movement of said element below a predetermined speed of rotation only, stationary means to limit the outward displacement of said element, and means operative at a higher speed of rotation to move said element radially inward from said stationary means to an optimum position and to secure it thereat.

70 8. In a suction cleaner, a cylindrical body, a brush element slideable radially with respect to the axis of rotation under centrifugal force mounted in said body, adjustable means within said body connected to and movable with said element, means preventing movement of said adjustable means below a certain speed of rotation

only, and centrifugally operated means to engage said adjusted means to position fixedly said element with respect to said cylindrical body at a higher speed of rotation.

9. In a rotary agitator for a suction cleaner, a cylindrical body formed with a radial brush seat, a brush element slidingly seated in said seat, a rotatable element within said body, linkage connecting said brush element to said rotatable element to rotate the latter upon radial movement of the former, and centrifugally operated means within said body to engage said rotatable element to move said brush element radially inward a predetermined distance at a predetermined speed of rotation.

10. In a rotary agitator for a suction cleaner, a cylindrical body formed with a radial brush seat, a brush element slidingly seated in said seat, a rotatable element within said body formed with teeth, linkage connecting said brush element to said rotatable element to rotate the latter upon radial movement of the former, a centrifugal weight mechanism having teeth, spring means acting upon said mechanism to cause teeth thereof to mesh with the teeth of said rotatable element to prevent movement of said brush element, said centrifugal weight mechanism being adapted to move under centrifugal force at a predetermined speed to disengage said teeth to permit said brush to move radially outward under centrifugal force, teeth of said mechanism engaging the teeth of said rotatable element upon continued movement of said mechanism under centrifugal force to rotate said element to move said brush element radially inward to a fixed position.

11. The construction defined in the preceding claim in which spaced diametrically opposed brush elements are connected to and movable with said rotatable element.

12. In a rotary agitator for a suction cleaner, a brush element, means supporting said element for rotation and for radial movement relative to the axis of rotation, means to lock said element at a radial position during agitator rotation, and means to effect the release of said element for radial movement upon the speed of agitator rotation decreasing below a predetermined point.

13. In a rotary agitator for a suction cleaner, a brush element, means supporting said element for rotation and for radial movement relative to the axis of rotation, a centrifugally actuated lock to maintain a radial setting of said element, and means to render said lock ineffective with said agitator rotating at less than a predetermined speed.

14. In a rotary agitator for a suction cleaner, a brush element, means supporting said element for rotation and for radial movement relative to the axis of rotation, agitator-rotation-controlled means to maintain said brush at a fixed radial extension during operation, and means to render said last-mentioned means ineffective at certain speeds of rotation of said agitator.

15. In a rotary agitator for a suction cleaner, a brush element, means supporting said element for rotation and for radial movement relative to the axis of rotation under centrifugal force, said brush element being adapted to move radially outward into contact with an abutting surface outside said agitator, and agitator-rotation-actuated means effective at and above a predetermined speed of rotation to withdraw said element a fixed distance radially inward from its outer

position in contact with the abutting surface to a radially fixed operating position and to lock it in such operating position.

16. In a rotary agitator for a suction cleaner, a brush element, means supporting said element for rotation and for radial movement relative to the axis of rotation under centrifugal force, and agitator-rotation-actuated means to move said element radially inward a constant and fixed distance only from the outermost position it assumes under centrifugal force.

17. The construction defined in the preceding claim in which said agitator-rotation-actuated means also locks said element in position.

18. In a rotary agitator for a suction cleaner, a brush element, means supporting said element for rotation and radial movement relative to the axis of rotation under centrifugal force, means connected to and rotatable upon radial movement of said element, and centrifugally operated means to rotate said rotatable means to move said element radially inward.

19. In a rotary agitator for a suction cleaner, a brush element, means supporting said element for rotation and radial movement relative to the axis of rotation under centrifugal force, means normally maintaining said element at a fixed radial extension and movable to disengaged relationship to permit said element to move radially outward, and means operable with said last mentioned means to engage said element and to move it to an optimum operating position.

20. In a rotary agitator for a suction cleaner, a cylindrical body formed with a radial brush seat, a brush element slidingly seated in said seat, a rotatable element in said body, means connecting said brush element to said rotatable element to rotate the latter upon radial movement of the former, a centrifugal-weight-operated mechanism adapted to engage said rotatable element to prevent movement thereof, spring means acting upon said centrifugal-weight-operated mechanism to urge it into engagement with said rotatable element, said centrifugal-weight-operated mechanism being adapted to move under centrifugal force to release said rotatable element to permit said brush to move radially outward under centrifugal force, said centrifugal-weight-operated mechanism being so constructed and arranged as to reengage said rotatable element upon continued movement of said mechanism under centrifugal force to fix the position of said rotatable element and said brush element.

21. In a suction cleaner, a plurality of brush elements connected for conjoint radial movement, means to lock said elements at a fixed radial extension at a constant speed of rotation, means to release said elements for outward radial movement during acceleration of the agitator, and stationary means to limit the outward radial movement of said elements.

22. In a rotary agitator for suction cleaners, a radially adjustable agitating element, means to release said element for radial movement between zero and full speed rotation, and means to lock said element at a fixed position with said agitator rotating at full speed rotation.

23. A rotary agitator for suction cleaners rotatable about an horizontal axis and comprising a radially fixed rigid beating element and a radially movable brushing element, and centrifugally operated means to lock said brushing element in operative position at a predetermined speed of agitator rotation.

24. In a suction cleaner rotary agitator rotatable about an horizontal axis, a rotatable body, an agitating element mounted for radial movement on said body and adapted to move outwardly under centrifugal force into a surface contacting position, and means operative at a predetermined speed of rotation to fix the radial position of said agitating element.

25. In a suction cleaner rotary agitator rotatable about an horizontal axis, a rotatable body, an agitating element mounted for radial movement on said body and adapted to move outwardly under centrifugal force into a surface contacting position, and centrifugal means oper-

ative at a predetermined speed of rotation to secure said agitating element in said surface contacting position.

26. In a rotary agitator for suction cleaners, a body rotatable about an horizontal axis, a brush element mounted for radial movement on said body and adapted to move radially outward into contact with an adjacent surface upon the rotation of the agitator, a centrifugal weight on said body and means actuated by said weight to secure said brush element relative to said body at a predetermined speed of rotation.

WILFORD G. KILPATRICK.

CERTIFICATE OF CORRECTION.

Patent No. 2,255,788.

September 16, 1941.

WILFORD G. KILPATRICK.

It is hereby certified that error appears in the printed specification of the above numbered patent requiring correction as follows: Page 2, first column, line 13, for "with this" read --within--; and second column, line 13, for the reference numeral "42" read --43--; page 5, first column, line 2, claim 8, for "adjusted" read --adjustable--; and that the said Letters Patent should be read with this correction therein that the same may conform to the record of the case in the Patent Office.

Signed and sealed this 4th day of November, A. D. 1941.

Henry Van Arsdale,

Acting Commissioner of Patents.
